EXHAUST VALVE FOR TORPEDO EXERCISE
HEADMerrill G. Leonard, Sharon, Pa., assignor to
Westinghouse Electric Corporation, East Pitts-
burgh, Pa., a corporation of Pennsylvania

Application August 5, 1944, Serial No. 548,277

4 Claims. (Cl. 114—20)

1

My invention relates to torpedoes and more particularly to blow-off valves for the exercise heads of torpedoes or any other tank or other normally closed chamber requiring a blow-off valve for the medium contained therein under pressure.

The Government of the United States has been granted a certain royalty-free license for governmental purposes with respect to the invention herein described.

Torpedoes when given an exercise run are provided with an exercise head. This exercise head is empty when in storage but just before a torpedo makes it exercise run, water, but preferably some solution for effecting proper balance is admitted to the exercise head. The amount of water, or other balancing liquid, placed in the exercise head is so chosen that the entire exercise head is substantially equal in weight to the war head for the torpedo.

Not to lose the torpedo at the end of an exercise run, means have to be provided for blowing the balancing liquid from the exercise head.

One object of my invention is the provision of valve means and a source of gas pressure that permits air or some other gas, as carbon dioxide, from the source of pressure to drive the balancing liquid out of the exercise head but does not permit entry of any sea water to the exercise head.

Another object of my invention is the provision of special check valve means for the exercise head of a torpedo.

Another object of my invention is the provision of effective blow-off means for torpedoes that are not affected by any of the usual positions a torpedo may take at the end of its run with reference to the earth's center of gravity.

A still further object of my invention is the provision of speed and pressure responsive blow-off means for torpedoes.

Other objects and advantages will become more apparent from a study of the following specification and claims and the accompanying drawing, in which:

Figure 1 is a somewhat schematic longitudinal sectional view of a torpedo exercise head provided with my invention;

Fig. 2 is a front view, with the upper part broken away, of a towing eye and valve shown in Figs. 1 and 3; and

Fig. 3 is a sectional view of my special blow-off valve and towing eye combination, the section being taken on section line III—III of Fig. 2.

A torpedo normally, because of its design, does not have a great tendency to roll about its longi-

2

tudinal axis, but at the instant the blow-off starts the initial air or other gas entering the exercise head may take such a position in the exercise head that the torpedo turns over on its back, or takes a nose up position. To prevent the loss of liquid expelling gas, I provide the construction shown generally in Fig. 1 and more in detail in Figs. 2 and 3.

The towing eye includes the base 37 welded or otherwise secured in a liquid tight manner to the exercise head 31. The base is provided with the nipple 32 having the flange 33, the valve seat 34 and the tube receiving projection 35.

A valve 36 having the rubber seal 38 is firmly held against the seat 34 by spring 39 and is guided to its proper position by guide stem 40 fitting into the projection 41 of the towing eye 42.

The towing eye 42 is provided with the openings 43 for discharging the water from the practice head. The towing eye is held to the base by bolts 44 and the base and nipple are secured to each other by screws 45. A suitable gasket 46 provides a liquid tight connection between nipple and base.

By means of a flexible connection 48, I connect the tube 49 to the projection 35. The tube 49 is provided with a weight 50 at its open end 51. Regardless of any tilting or rolling of the torpedo, the weight 50 will always position the opening 51 at the lowest point. When the depth responsive device or the speed responsive device, not shown, or both, operate, the gas enters the exercise head at 52 and the pressure in the head compresses spring 39 and the liquid in the head is forced into the open end 51 and through the valve and out of the openings 43.

I do not wish to be limited to the particular showing and disclosure made but wish to be limited only by the claims hereto appended.

40 I claim as my invention:

1. In mechanisms for discharging the torpedo balancing liquid, in the exercise head of a torpedo from the exercise head at the end of an exercise run to make the torpedo buoyant, in combination, a cylindrical member having an outer end hermetically sealed to the inner surface of the nose of a head directly adjacent to an opening in the nose of the head, said cylindrical member having a re-entrant portion at its inner end designed as an annular valve seat, a valve plate disposed to rest on the valve seat, a towing eye for the head designed as a spider rigidly secured to the nose of the head over the opening in the nose, and spring means, under selected compression disposed between the spider-like towing eye and the valve

for holding the valve on the seat with a predetermined force.

2. In mechanism for discharging the torpedo balancing liquid, in the exercise head of a torpedo from the exercise head at the end of an exercise run to make the torpedo buoyant, in combination, a cylindrical member having an outer end hermetically sealed to the inner surface of the nose of a head directly adjacent to an opening in the nose of the head, said cylindrical member having a re-entrant portion at its inner end designed as an annular valve seat, a valve plate disposed to rest on the valve seat, a towing eye for the head designed as a spider rigidly secured to the nose of the head over the opening in the nose, spring means, under selected compression disposed between the spider-like towing eye and the valve for holding the valve on the seat with a predetermined force, and guide means on the valve and towing eye for maintaining the spring means in correct position with reference to the valve, valve seat, and towing eye.

3. In mechanisms for discharging the torpedo balancing liquid, in the exercise head of a torpedo from the exercise head at the end of an exercise run to make the torpedo buoyant, in combination, a cylindrical member having an outer end hermetically sealed to the inner surface of the nose of a head directly adjacent to an opening in the nose of the head, said cylindrical member having a re-entrant portion at its inner end designed as an annular valve seat, a valve plate disposed to rest on the valve seat, a towing eye for the head designed as a spider rigidly secured to the nose of the head over the

opening in the nose, spring means, under selected compression disposed between the spider-like towing eye and the valve for holding the valve on the seat with a predetermined force, and a weighted flexible tube connected to the inner end of the cylindrical member for at all times collecting the liquid within the head, when subjected to pressure for expelling it, from the lowermost region of the head.

10 4. In mechanisms for discharging the torpedo balancing liquid, in the exercise head of a torpedo from the exercise head at the end of an exercise run to make the torpedo buoyant, in combination, a cylindrical member having an outer end hermetically sealed to the inner surface of the nose of a head directly adjacent to an opening in the nose of the head, said cylindrical member having a re-entrant portion at its inner end designed as an annular valve seat, a valve plate disposed to rest on the valve seat, a towing eye for the head designed as a spider rigidly secured to the nose of the head over the opening in the nose, and spring means, under selected compression disposed between the spider-like towing eye and the valve for holding the valve on the seat with a predetermined force, guide means on the valve and towing eye for maintaining the spring means in correct position with reference to the valve, valve seat and towing eye, and a weighted flexible tube connected to the inner end of the cylindrical member for at all times collecting the liquid within the head, when subjected to pressure for expelling it, from the lowermost region of the head.

35 MERRILL G. LEONARD.
